BRASSIÈRE

Adrienne Hirsch, New York, N. Y.

Application January 6, 1934, Serial No. 705,476
Renewed June 4, 1936

4 Claims.

(CL. 2—42)

This invention relates to brassières.

An object of this invention is to provide a highly improved brassière having two cup portions for receiving the breasts, and being so constructed that the breasts are lifted without pressing down or flattening the top of the breasts.

Another object of this invention is to provide a highly improved and economical method of making a brassière of the character described.

10 A further object of this invention is to provide a neat brassière of the character described, which shall comprise comparatively few and simple parts, be economical of manufacture, comfortable to wear, and nevertheless practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is a perspective view of a brassière embodying the invention, shown in position for use, with parts torn away to show other parts;

30 Fig. 2 is an elevational, cross-sectional view taken along the mid-section of the brassière;

Figs. 3 and 4 are top plan views of the blanks for the upper and lower portions of the cup respectively; and

35 Fig. 5 is a front view of one of the cup portions of the brassière.

Referring now in detail to the drawing, 10 designates a brassière embodying the invention, here seen to comprise two similar, symmetrically disposed cup-shaped portions 11 stitched together in the manner hereinafter appearing. Each cup-shaped portion 10 comprises an upper section 13 and a lower section 14. The upper sections 13 may each be formed with a piece or blank of cloth shown in Fig. 3, and each lower section 14 may comprise a piece or blank of cloth shown in Fig. 4 of the drawing. The piece of cloth 13 has a lower edge marked ABC, on Fig. 3 of the drawing, the edge portions AB and CB being substantially straight, and said edge portions being inclined downwardly and inwardly, forming a point at B. The upper edge of the section 14 is indicated on Fig. 4 by the letters DEF, the edge portions DE and FE being inclined upwardly and inwardly and forming a rounded apex at E.

In making the cup-shaped portion 11 on the left of the drawing, (looking at Fig. 1), the edge ABC is stitched to the edge DEF. However, the edge ABC is preferably longer than the edge DEF to give extra material in the lower edge of the top section for producing a roundness which prevents the top section from pressing down on the breast. Preferably the edge portion CB is larger than edge portion FE and edge portion AB is larger than edge portion DE. The top section is thus cupped to receive the lifted breast. In sewing the top section to the bottom section, the stitching should allow for a gradual absorption of the difference in length to minimize the visibility of the puckering. Further, the point B should meet the point E. The cup-shaped portion 11 on the right of the brassière, looking at Fig. 1, is also made of two pieces of cloth shown in Figs. 3 and 4, the same being inverted from left to right, however, whereby the cup-shaped portions are similar and symmetrically disposed to one another.

Furthermore, the top sections 13 are preferably made of a relatively light, soft, loosely woven material, such as lace or net, whereas the bottom sections 14 are made of a stronger or heavier and more tightly woven material such as satin or broadcloth, having less elasticity. The advantage of this construction is that the lower sections lift the breasts but because the top sections are made of a softer material, the breasts are not pressed down against the bottom sections and there is therefore no tendency to flatten the breasts. If the top sections were also made of heavy material there would be more likelihood of an equal upward and downward pressure on opposite sides of the breasts, tending to flatten the same. With my improved construction, the bottom sections uplift the breasts and the top sections tend to keep them round and assume the natural shape of the top of the breasts.

The straight of the material of the sections 13 and 14 may be substantially on horizontal lines, looking at Figs. 3 and 4. The straight of the material, therefore, substantially runs from the point C to somewhat above the point A on the sections 13; and from the point F substantially to the point D on the sections 14. With this construction the straight of the material of the lower sections 14 from the outer points D and F is substantially mid-way below the breasts to permit said lower sections to properly uplift the breasts.

The edges DE and FE are, however, cut on the bias to permit some stretching or give at the seam between the sections 13 and 14. Likewise

the edges AB and CB of the upper sections 13 are cut on the bias to permit a give or provide for stretching, at said seam, for rounding off the cup portions 11 to accommodate and comfortably fit the breasts. The upper sections thus partly conform to the breasts.

By making each cup portion 11 of two separate sections, the bias and the straight of each section can be located in the proper place. If the 10 two upper sections, for example, were made of one piece, the straight of the material could not be located properly. The same is true of the lower sections. The upper sections 13 are preferably cut full to cover the entire breasts and 15 prevent bulging of the breast above the upper edges of the brassière.

The section 13 is provided with an inner edge designated AG inclined upwardly and outwardly. The edges AG of the two sections 13 are stitched 20 together in a seam 15. Due to the inclination of the edges AG, therefore, the seam 15 is inclined upwardly and inwardly toward the body. The lower sections 14 have inner edges DH inclined 25 downwardly and outwardly. The edges DH of the two sections 14 are stitched together in seam 16, and said seam inclines downwardly and inwardly toward the body, thus further fashioning the cup-shaped portions.

A band 17 is stitched to the bottom edges HI 30 of the lower sections 14 and is adapted to lie flat against the chest below the breasts and prevent slipping downwardly of the breasts.

Outwardly tapering sections 18 may be stitched 35 to the outer edges IF, CJ of the sections 13 and 14 to form seams 19. An elastic strip or band 20 may be stitched to the outer end of one of the sections 18 and provided with hooks or any other suitable fasteners 21 for attachment to eyelets at the outer end of the other section 18. 40 Shoulder straps 23 may be attached to the upper ends of the sections 13 and to the ends of the sections 18, respectively.

It will thus be seen that there is provided a device in which the several objects of this invention are achieved, and which is well adapted to meet the conditions of practical use.

As various possible embodiments might be made of the above invention, and as various changes might be made in the embodiment set forth, it is to be understood that all matter herein set forth or shown in the accompanying drawing is to be interpreted as illustrative and not in a limiting sense.

Having thus described my invention, I claim as 55 new and desire to secure by Letters Patent:—

1. In a brassière, two cup-shaped portions, each cup-shaped portion for receiving the breast and comprising an upper section and a lower section, the upper section being made of a piece 60 of cloth having a lower edge formed of two inwardly and downwardly diverging portions and the lower section being formed of a piece of cloth having an upper edge having two upwardly

and inwardly diverging portions, the lower edge of the upper section being stitched to the upper edge of the lower section, and said lower edge of the piece which forms the upper section having a greater linear length than the upper edge 5 of the piece which forms the lower section.

2. In a brassière, two cup-shaped portions, each cup-shaped portion for receiving the breast and comprising an upper section and a lower section, the upper section being made of a piece 10 of cloth having a lower edge formed of two inwardly and downwardly diverging portions and the lower section being formed of a piece of cloth having an edge having two upwardly and inwardly diverging portions, the lower edge of the 15 upper section being stitched to the upper edge of the lower section, the lower edge of the piece which forms the upper section having a greater linear length than the upper edge of the piece which forms the lower section, the diverging 20 portions of the lower edge of the upper section and the diverging portions of the upper edge of the lower section being cut on a bias.

3. A brassière comprising two cup-shaped portions, each cup-shaped portion comprising an 25 upper section and a lower section, the lower edge of each upper section being stitched to the upper edge of each lower section, and the inner edges of said upper sections being stitched together, and the inner edges of said lower sections being 30 stitched together, the entire lower edge of each upper section and the entire upper edge of each lower section being cut on the bias, said upper sections being made of a relatively extensible cloth, and said lower sections being made of relatively inextensible cloth, said upper sections 35 being formed of pieces of cloth having the inner edges thereof inclined upwardly and outwardly, and said lower sections being formed of pieces of cloth having the inner edges thereof inclined 40 downwardly and outwardly.

4. A brassière comprising two cup-shaped portions, each cup-shaped portion comprising an upper section and a lower section, the lower edge of each upper section being stitched to the upper 45 edge of each lower section, and the inner edges of said upper sections being stitched together, and the inner edges of said lower sections being stitched together, the entire lower edge of each upper section and the entire upper edge of each 50 lower section being cut on the bias, said upper sections being made of a relatively extensible cloth, and said lower sections being made of relatively inextensible cloth, said upper sections 55 being formed of pieces of cloth having the inner edges thereof inclined upwardly and outwardly, and said lower sections being formed of pieces of cloth having the inner edges thereof inclined downwardly and outwardly, and the lower edge of each upper section being of greater length 60 than the upper edge of each lower section.

ADRIENNE HIRSCH.
